UNITED STATES PATENT OFFICE.

ALVIS RIEDLER, OF AACHEN, PRUSSIA, GERMANY.

VALVE-GEAR.

SPECIFICATION forming part of Letters Patent No. 395,174, dated December 25, 1888.

Application filed March 31, 1888. Serial No. 269,149. (No model.) Patented in Germany December 23, 1886, No. 42,346; in Austria-Hungary December 24, 1886, No. 35,379 and No. 65,621; in France January 19, 1887, No. 181,005, and in England January 19, 1887, No. 855.

To all whom it may concern:

Be it known that I, ALVIS RIEDLER, a subject of the King of Prussia, Emperor of Germany, residing at the city of Aachen, in the 5 Kingdom of Prussia, Empire of Germany, have invented certain new and useful Improvements in Valve-Gear, (for which Letters Patent have heretofore been granted to me in Germany, No. 42,346, dated December 23, 1886; 10 in Austria-Hungary, No. 35,379 and No. 65,621, dated December 24, 1886; in France, No. 181,005, dated January 19, 1887, and in England, No. 855, dated January 19, 1887,) of which the following is a specification.

15 This invention relates to improvements in valves for pumps and air-compressors that open automatically, but are closed by the action of a separate power—for example, the pressure of a spring, weight, or liquid under 20 pressure.

The invention consists in the combination, 25 with a valve, of a downwardly-pressing spindle above it, a rocking lever-arm for raising the spindle, and mechanism for operating the 30 rocking lever-arm from the motor of the pump or air-compressor. The valve-gear does not raise the valves, but raises the rods above them, thus permitting the valve to open, and 35 then the valve-gear permits the downwardly-pressed rod to descend slowly and close the valve.

In the accompanying drawing a diagrammatical side view of my improved valve-gear is shown, parts being broken out and others 35 being in section.

v is the pressure-valve, and *v'* the suction-valve. Above the two valves *v* and *v'* the two spindles *s* and *s'*, respectively, are mounted to slide vertically in suitable stuffing-boxes, 40 *t* and *t'*, in the valve-casing *A*. Said spindles *s* and *s'* are not connected with the valves *v* and *v'*, but are pressed downward at all times by a separate and independent source of force or power, which in this case consists of a spring, *f*, for 45 the spindle *s* and for the spindle *s'*, of a liquid under pressure acting on the upper end of the spindle *s'* in the cylinder *c*, in the stuffing-box of which cylinder the said spindle *s'* slides. The spindles thus have the tendency,

under the action of the spring *f* and liquid 50 under pressure, respectively, to move downward and to press down and close the valves *v* and *v'*. Between the spindles *s* and *s'* the rock-shaft *w* is mounted, and from the same the two lever-arms *h* and *h'* project in opposite directions, and 55 an arm, *h*, projects downward at right angles to the lever-arms *h* and *h'*. The ends of the arms *h* and *h'* enter slots in the spindles *s* and *s'*, or rest against projections of said spindles, and the arm *h* is connected by means of a rod, *a*, 60 either directly or by intermediate rods, *r*, with a crank or eccentric, *b*, from which the arms *h* and *h'* are thus rocked. During the time the eccentric moves from *e* to *e'* the arm *h* raises the spindle *s*, that is pressed down by 65 the liquid in the cylinder *c* from the valve *v*, thus permitting said valve to rise and open. When the arm *h'* swings down, the spindle *s'* is pressed down by the liquid acting on its upper end, and said rod *s'* presses the valve 70 *v'* upon its seat and closes it. The valve is not closed abruptly, as the spindle rests upon the end of the lever-arm *h'* and cannot descend any faster than said lever-arm. During 75 the time the lever-arm *h'* moves upward the lever-arm *h* moves downward, and the spindle *s* is pressed downward by the spring *f* and closes the valve *v*. During the downward movement of the lever-arm *h'* the lever-arm *h* rises and raises the spindle *s* from the valve 80 *v*, thus permitting said valve to rise.

In the case the valve-gear eccentric does not change its stroke at the same time the pump piston-crank does—for example, when the end of the pump piston-crank is at *k*, and 85 the connection of the rod *r* and the eccentric is at *e*—the eccentric will move from the point *e* to the point *e'* before the stroke of the valves changes. When the eccentric is at *e*, the valve *v* has already been closed, and during the time 90 the eccentric moves from *e* to *e'* the lever-arm *h* swings downward in the slot of the spindle *s*, and the spring *f* keeps the valve *v* closed. At the same time the lever-arm *h'* raises the spindle *s'* more than is necessary. All this, 95 however, has no influence on the operation of the valves.

When the eccentric of the valve-gear and

the pump-piston change their stroke at the same time—that is, when the angle $g=0$ —or in the case the arm h^2 is operated by a rod that reciprocates with the pump-piston, the 5 above movements do not take place, but the valves open and close in the usual manner.

It is not absolutely necessary to operate both valves v and v' by the same gear, as the spindle above each valve may be operated 10 from a separate eccentric. The valves v and v' may have one or more seats, as may be desired.

In case springs are to be used exclusively for pressing the spindles upon the valves, they 15 may be located within the valve-casing A. The rocking-shaft W can be mounted to pass through stuffing-boxes and transversely through the valve-casing A, the lever-arms h h' being within the valve-casing. The valve- 20 gear may be operated by any eccentric or crank, and any eccentric on the motor-engine of the pump may be used for this purpose. Any rod reciprocating with the pump-piston may be used for operating the spindles s and 25 s' either directly or indirectly. The reciprocating rod may be operated from the main crank of the shaft instead of by a separate eccentric.

It is essential in all constructions that the 30 reciprocating or rotary motion of the driving element have sufficient power to overcome the pressure exerted on the spindles before the valves begin to open, and that the said pressure can operate freely when the valves are 35 to be closed. In all cases the valve-gear never opens the valves and only closes them by intermediate mechanism.

Having thus described my invention, I claim as new and desire to secure by Letters Patent—

40

1. The combination, with a valve of a pump or air-compressor, of a constantly-compressed spindle adjacent to the valve, said spindle being independent of and not connected with said valve, and a lever acting on 45 the spindle, as described, so as to impart a positive oscillating motion to said spindle, substantially as set forth.

2. The combination, with the valve of a pump or air-compressor, of a constantly-pressed 50 spindle adjacent to said lever, said spindle being independent of and not connecting with said valve, a lever acting on the spindle, a crank or eccentric, and a rod operating the fulcrumed lever from said crank or eccentric, 55 substantially as set forth.

3. The combination, with a valve casing or casings, of valves in the same, a constantly-pressed spindle adjacent to each valve, a rocking shaft, lever-arms on said shaft engaging 60 the spindles, and mechanism, substantially as described, connecting said rocking shaft with a movable element of the pump or air compressor, substantially as set forth.

In testimony whereof I have signed my 65 name to this specification in the presence of two subseribing witnesses.

ALVIS RIEDLER.
